In Germany April 1, 1938

20 Claims. (Cl. 179—17)

The present invention relates to party lines in remote signalling, in particular telephone installations in which for the selecting of a required branch set selecting impulses of different duration and direction control condenser receiver arrangements at the branch set. In known arrangements a selection among six sets is possible, since the condenser arrangement at the individual branch sets are controlled by positive or negative impulses of short, medium and long duration during the selector operation.

The present invention has as its object the increasing of the number of branch sets which can be connected to the party line and selected by selecting impulses of various duration and direction and in order to obtain this result a selecting current of particular direction and duration marks a number of branch sets whose connecting relays at the end of the selecting current are connected to the party line in a number of different ways so that only the connecting relay at the selected branch set is maintained energized and the current source in the exchange necessary for maintaining different energies is connected to the party line in a manner peculiar to the selected branch set.

With the arrangement according to the invention the selection among eight branch sets is possible by using only two selecting impulses i. e. positive and negative which are differentiated in their duration. By further dividing up of the duration of the selecting impulses the number of branch sets which can be selected is considerably increased thus for example when the duration of the current is divided into three stages, namely, selecting currents of short, medium or long duration each of sixteen branch sets connected to the party line can be individually connected with complete certainty.

In the drawings two embodiments of the invention are shown. Figs. 1-3 show one embodiment and Figs. 4-6 the second embodiment.

In both embodiments party lines of the eight branch sets are considered.

Figs. 1 and 4 show the apparatus and circuits of the two branch sets.

Figs. 2A, 2B and 5A, 5B show the arrangements associated with the party line in the exchange.

In Figs. 3 and 6 marking signals in the individual branch set of the party line are shown and the wiring of the arrangements provided equally at all the branch sets.

I. EMBODIMENT ACCORDING TO FIGS. 1-3

(1) The branch set AS₆ makes a call and is connected

The subscriber of the branch set AS₆ takes up his handset. The switch hook contact 6hu1

is closed and thereupon the switchhook hu6II is opened. The ringing circuit is completed: earth, contact 11b6, winding I and II of the relay Sp6, switchhook contacts hu6II, hu6I, impulse contact nsi, connection 7, conductor 1a, contacts 12ba, 13v1, 14g, 15p, 16c, winding I of the relay An, —. The relays Sp6 and An operate. The relay Sp6 short circuits the winding I at contact 11sp6 and at contact 18sp6 prepares a dialling circuit over its winding III.

The relay An connects this in a locking circuit: +, contact 19kr2, wiper 20 of the indication switch KW1, normal position of this, contact 21an, winding II of the relay An, —. At contact 22an, the setting of the marking selector is prepared. The relay A is connected over relay 23an to the conductor 1a. At contact 24an the relay J is connected and opens contact 25j and closes contact 28j. The negative pole of a battery of 120V is applied to the conductor 1b over the resistance 27. The lamps in the branch sets of the conductor 1b light up. The B-relay is connected in series with the lamps operated.

In the exchange the lamp G1a is not lit up, accordingly the relay Ba cannot operate since earth is disconnected by means of contact 28an. The energized circuit for the relays B6 and B7 at the branch sets AS₆ and 7 extends as follows: 120V, resistance 27, contact 28j, conductor 1b, branch set AS₆, connection 8, lamp G16, winding II and I of the relay B6, earth and branch set AS₇, connection 8, lamp G17, winding II and I of the relay B7, earth. The contacts 11b6 (AS₆) and 29b7 (AS₇) are opened and the contacts 30b6 (AS₆) and 31b7 (AS₇) are closed. The B relays guard all the branch sets not in the calling condition since contact 29b7 and the corresponding contacts in the branch sets AS₁, 5 and 6 are opened.

At the calling branch set AS₆ the relay Sp6 remains energized: earth, contact 30b6, winding III of the relay Sp6, contacts 18sp6, 32s6, hu6I, nsi, connection 7, conductor 1a, contact 12ba, 23an, relay A, contact 33u1, resistance 34; —. The relay operates over the contacts: 35w or 175x, 36a relay V1, resistance 37, —. At contact 38v1 a circuit is prepared for only V2, but this cannot yet operate due to the short circuit extending over: +, contacts 35w or 175x, 36a, windings II and I of relay V2, contact 38v1 and +. At contact 39v1 a circuit is prepared over the rotary magnet Dkw1 of the indicating selector KW1.

The calling subscriber selects his characterizing digit 6, by operating a special finger hole in his dial switch for transmitting pre-setting impulse trains. All subscribers in making a call operate their dial switches in the same manner.

However only the impulses corresponding to their own characterizing digit are sent out. After the transmission of these impulses there follows the short-circuiting of contact $ns1$ on the closing of contact nsa . The transmission of the pre-setting impulse train can also take place in a different manner, e. g. automatically on the taking up of the instrument or by operating the finger plate corresponding to the subscriber's own number.

In the exchange the impulse trains are transmitted by the relay A to the rotary magnet $Dkw1$ of the marking switch over: +, contacts $22an$, $41ab$, $42h$, $43a$, $39v1$, $44p1$, $45p$, rotary magnet $Dkw1$, -. During this impulse train the relay $V2$ is also energized since by the opening of contact $36a$ the short circuit for winding I and II is removed. At contact $46v2$ it short circuits its winding II and holds its armature attracted during the impulse train. After the wiper 20 of the marking switch $KW1$ and the back contact has left its normal contact the relay An remains energized since at contact $47v2$ its winding II is connected. The momentary closing of contact $48a$ occurring during the impulse transmission does not result in the release of relay $V1$.

At the end of the pre-setting impulse train the relay A remains energized. Contact $36a$ is permanently closed. The relay $V2$ restores. At contact $47v2$ relay An is disconnected and earth (+) connected over contact $28an$ to the relay Ba . This relay is energized by the battery from $-120V$ connected over the contact $26j$ and operates its contacts. The relay P is energized: +, contacts $49v1$, $50an$, relay P , -. Parallel to the contact $49v1$ is contact $51ba$, so that the relay P remains energized after the release of relay $V1$. Over the series of contacts $197c$, $52y$ and $53p$ the relay J is maintained energized after the opening of contact $24an$.

The relay A is disconnected at contact $23an$. The contact $36a$ is opened and contact $48a$ is closed. The relay $V1$ restores and among other things closes contact $59v1$. Since now the contact $12ba$ is open and contact $61ba$ closed, the connecting signal associated with branch set $AS16$ is applied to the party line.

In Fig. 3 the connecting signals associated with the individual branch sets in the party line are arranged in the form of a table. From this it is clear for the connection of each branch set a selecting impulse of particular polarity (negative or positive) and particular duration (short or long) is necessary and that further the holding windings of the connected relays are either connected to the conductor $1a$ or to conductor $1b$.

In order to connect the calling branch set $AS16$ a long negative impulse is necessary by which however branch set $AS17$ is also marked. The holding of the connecting relay $R6$ takes place over conductor $1b$ and the holding of relay $R7$ over the conductor $1a$.

The selection of the connecting signal is performed by means of the indicating selector $KW1$ operated by the presetting impulse train the wipers of which are raised on to contact 6 . The long negative impulse marking of the two branch sets $AS16$ and $AS17$ controls the condenser resistance arrangements at the branch sets of the following circuit: contact 6 , wiper 54 of the connected switches $KW1$, contacts $58kr3$, $59v1$, $60j$, $61ba$, conductor $1a$, at all branch sets over the condenser KO to earth and to the calling branch set $AS16$ over resistances 65 , 66 , junctions 3 , 1 , contact $67b6$, condenser $Ko6$, earth, and at the other branch sets $AS17$ shown over resistances 75

62 , 63 , junctions 3 , 1 , contact $64b7$, condenser $Ko1$, earth. Also at the branch sets 5 and 8 the condensers are connected with two series resistances corresponding to the resistances 65 , 66 ($AS16$).

5 At the branch sets 1 — 4 the junctions 1 and 2 are connected. The condensers are connected over the resistance 65 , corresponding to the resistance at the junction 7 and thence to the conductor $1a$.

On the release of relay $V1$ the relay Y is connected: +, contacts $68p$ and $69v1$, relay Y , winding I, -. This holds over winding II and the contact $70y$. The relay J is disconnected at contact $52y$. Since a long impulse is necessary for selecting the branch set $AS16$ the relay J must

13 not yet restore and open the contact $60j$ in the charging circuit for the condensers at the branch sets. In order to slow up its release the relay J connects the slow relay E : +, contact $19kr2$, wiper 20 , contacts 6 , $57j$, relay E , -. The relay E switches over the condenser 73 from charging circuit extending over the normal contact $72e$ to discharge circuit extending over relay J . After the opening of the contacts $52y$ there follows the discharging of the condensers 73 over contact $74e$ and relay J , during which the relay J holds its armature attracted.

After the release of relay J the first discharging circuit for the condensers at the branch sets is closed over conductor $1a$ of the party line so that the condensers discharge. The condensers at the branch sets 5 to 8 are also discharged. Since the discharging circuit at these branch sets also extends as does the charging circuit over two resistances in series at the branch sets $AS16$ and $AS17$, e. g. over the resistances 65 , 66 and 62 , 63 , those condensers after the interruption of their first discharging circuit will have a charging which is sufficient to operate the start relays (e. g. relay $R6$ at $AS16$ and relay $R7$ at $AS17$) when the local discharging circuits are closed.

The relay J restoring after the discharge of the condenser 73 in the exchange among other things closes its contacts $25j$, $75j$ and opens the contacts $26j$, $60j$, $57j$. The relay Ba in the exchange and also the B relays at the branch sets remain energized since over the contact $76e$ the current source $-120V$ is still connected to the conductor $1b$. During the release period of the relay E earth is applied over the contacts $11e$, $75j$, $61ba$ to the conductor $1a$ and thus the first discharging circuit for all the condensers is set up at the branch sets.

The relay E restores and at contact $77e$ disconnects the current source $-120V$ maintaining the B relay energized from the conductor $1b$. The latter is switched through at contact $78e$. The relay Ba in the exchange and the B relays at all branch sets restore. At contact $12ba$ the conductor $1a$ is switched through. The condensers of the branch sets are disconnected from the conductor $1a$ and connected in local discharge circuits over the normal contacts of the B relays. At the calling branch set $AS16$ the local discharging circuit of the condenser $Ko6$ extends over the contact $80b6$ and the winding I of the relay $R6$ and at the branch set $AS17$ marked by the same selecting current (long negative impulse), over the contact $19b7$ and the winding I of the relay $R7$. The relays $R6$ and $R7$ operate and among other things connect their holding winding by closing contacts $81r6$ and $82r7$. The same procedure results at the branch sets $AS15$ and $AS18$. At the branch set $AS17$ and also at the branch set $AS15$ the holding winding II of the connecting relay is connected over the junc-

tion 1 with the conductor 1a while at the branch sets AS₆ and AS₈ the holding winding II of the R relay is connected over the junction 8 to the conductor 1b.

The connecting relays of the group marked by the same selecting current (long negative impulse) are connected in various manners to the party line and actually in the branch set (AS₆ and AS₇) to the conductor 1b and in the branch set AS₇ is to the conductor 1a.

Since the branch set AS₆ is to be connected at this branch set the winding II of the relay R is connected with the conductor 1b and the unearthened pole (—) of the central battery is connected to this conductor in the exchange at the conductor 1b over resistance 34, contact 33u1, relay A, contacts 83y, 84w. Holding current can accordingly not flow over the winding II of the relay R7 connected to the conductor 1a and to the branch set AS₇ marked by the same selecting current as the branch set AS₆. The connected relays R at the branch sets AS₅ and AS₈ are also energized in the discharging circuits of the condensers. The holding winding of the relay branch set AS₅ is connected to the conductor 1a according to Fig. 3. This relay cannot hold and therefore restores. The holding winding of the start relay of the branch set AS₈ as well as those of the calling branch set AS₆ are connected to the conductor 1b. However, this relay also restores since the holding winding is connected in similar manner to that at the branch set AS₇ i. e. in the opposite direction to that of the branch set AS₆. The junctions 4, 6 and 5, 8 are connected together. The holding circuit over the winding II of the start relay at the branch set AS₈ therefore effects a reversal of the polarization so that this start relay restores. Therefore only the connecting relay R6 at the branch set AS₆ remains energized.

In the holding circuit of the winding II of the relay R6, the relay A in the exchange operates and at 36a connects the relay V1. Since the relay Y is also energized the conductors 106 and 107 extending to the preselector VW are switched through at the contacts 104a and 105y. The calling relay of the preselector, not shown, closes the circuit over the choke Dr2. The preselector is set on a free outgoing junction line.

On the energization of the start relay R6 there follows the connection of the talking apparatus, which is indicated by the microphone Mi, to the party line. In addition to the circuit of the winding II of the relay R6 the following circuit is completed: +, contact 89u1, choke Dr1, contact 100y, 101w, 12ba, conductor 1a, contacts ns1, hu6I, 108r6, winding I of the relay S6 operator's equipment, contacts 109b6, 110r6, connection 8, conductor 1b, contacts 25j, 78e, 84w, 83y, relay A, contact 33u1, resistance 34, —. The relay S6 operates. It closes the contacts 110r6 and 108r6 parallel to the contacts 111s6 and 114s6 and disconnects earth from the winding II of the connected relay R6 at contact 112s6 this relay restoring. At the same time the dissymmetry in the talking conductors brought about after the selection of the branch set AS₆ by the connection of the winding II of the relay R6, is removed. At contact 113s6 the winding I of the relay B6 is short-circuited. The contact 32s6 is also opened.

The connection of the branch set AS₆ to the party line is completed.

After the opening of the contact 69v1 the relay

Y in the exchange remains energized over its winding II and the contacts 70y, 68p. Further the relay V1 undertakes the necessary switching operations for setting up the connection to be extended from the calling subscriber.

The transmission of the presetting impulse train not only results in the connection of the marking signal associated with the calling set AS₆ but also the preparatory connection of the associated meter Z6 in the exchange which is connected over the wiper 103 parallel to the blocking winding of the cut-off relay of the pre-selector VW. The connection of the branch set AS₆ by means of a long negative impulse operating on the condenser resistance arrangements and also marking the branch set AS₇ has been described and how by the various connections of start relays of those branch sets AS₆ and AS₇ to the party line, in conjunction with the connection of the unearthened pole of a battery determined by the selecting operation (to the conductor 1b) only the connection of a branch set (AS₆) is finally brought about.

By every other selecting current whether it be different in direction or duration or direction and duration a number of other branch sets (in the embodiment always a group of two branch sets) are marked. Thus the long positive impulse marks the branch sets AS₅ and AS₈ the short negative impulse marks the branch sets AS₂ and AS₃ and a short positive impulse marks the branch sets AS₁ and AS₄. The final connection of the particular branch set always follows in such a manner that the start relay of the previously marked branch sets are connected in different manner to the party line and only the start relay of the branch set to be connected remains energized since for this relay a suitable holding circuit is set up in the exchange.

(2) *Connection of the branch set AS₆ with the branch set AS₇*

The subscriber of the branch set AS₆ wishes to speak with the subscriber of the branch set AS₇. He first selects the marking digit for his own line. The corresponding dial impulses operate on the group and final selectors and also on the indicating selector KW2 on the party line. After this has been set corresponding to the subscriber's digit of the same line the operating group and final selector release. The completion and maintenance of the connection are performed by the apparatus associated with the party line.

The relay P energized after the release of the relay An has disconnected the rotary magnet Dkw1 of the indicating selector KW1 at contact 45p and therefore over the contact 113p the rotary magnet Dkw2 is brought under the control of the impulse contact 43a. The circuit in the rotary magnet Dkw2 is prepared at contact 119g by means of the relay G. This relay is energized after the energizing of the relay Y: +, contacts 112p, 115v1, 116y, 117h, relay G, —. It holds over its own contact 118g during the time in which the relay is restored.

By means of the impulses sent out from the calling set the group selector and the final selector in the exchange are set by means of contact 104a and also by means of the contact 43a of the marking selector which acts as a discriminator. The characterizing digit of the party line on which the branch sets AS₆ and AS₇ are connected is "2422". The discriminator must ac-

cordingly be set by four impulse trains having respectively 2, 4, 2 and 2 impulses. If any of these 4 impulse trains consists of a different number of impulses there follows a disconnection of the marking selector **KW2** since then the condition is satisfied that these impulse trains have not suitable values for setting up a connection at the branch set on the calling party line and that a connection with a remote junction line is to be seized. By means of each impulse train which operates on the marking selector its wipers **120**, **121**, and **122** are stepped on. All the contacts **0-18** are only shown as passed over by the wiper **120** while of the contacts over which the wipers **121** and **122** are moved only contacts **11-18** are shown since over the contacts **1-10** switching operations are performed which are of no concern for the connection to be described.

By means of the first impulse train the wipers are set on the selector contact **2**. After the release of the relay **V2** energized during each impulse the marking relay **Kr1** is energized: +, contacts **123ab**, **124v2**, wiper **120**, switch contact **2**, winding I of the relay **Kr1**, -. The relay **Kr1** locks up: +, contacts **125ab**, **126kr1**, winding II of the relay **Kr1**, resistance **121**, -. At contact **128kr1** it opens the connection between the contacts **5** and **6** and connects the winding I of the marking selector to the latter over its contact **129kr1**. Further the contact **130kr1** in series with the winding I of the marking selector **Kr3** is opened.

By means of the second impulse train which has four impulses, the selector is set on the marking contact **6**. After the closing of the contact **124v2** the marking relay **Kr2** operates and locks up over contact **130kr2** and its winding II. At contact **131kr2** it opens the connection of the selector contacts **7** and **8** and at the latter connects the holding winding II of the marking relay **Kr1** over the contact **132kr2**.

The third impulse train brings the selector on to the marking contact **8**. On the closing of contact **124v2** the marking relay **Kr1** is restored since its holding winding II is short circuited. Positive is connected to the lower end of the winding over contacts **125ab** and **126kr1**. After the closing of contact **124v2** positive is connected also to the upper end of the winding over contacts **123ab**, **124v2**, **120**, **8**, **132kr2**. The contact **126kr1** is opened and the contact **130kr1** is closed.

The last impulse train for marking the same line sets the marking selector on contact **10**. Since the marking relay **Kr3** is connected to this selector contact with its winding I over the series contact **130kr1** and **134kr2**, it operates after the release of the control relay **V2**. Thus the marking signal which indicates that the connection with the branch set of the calling party line has been set up is sent out.

The relay **Kr3** therefore locks up over its winding II and the contact **135kr3** by opening the contacts **136kr3** and **137kr3** and disconnects its selector contacts **9** and **11** and **14** and **15**. At contact **138kr3** an energizing circuit for the relay **H1** is prepared and contact **139kr3** the conductor **107** is disconnected. In this way the release of the set selector is initiated at the exchange since the loop maintaining the bridge relay at a subsequent point in the connecting path is opened over the choke **Dr2**.

If any of the impulse trains do not have the value for marking its own line the setting of the wipers of the indicating selector one after

another on the marking contacts **2**, **6**, **8** and **10**, does not take place. If, for example, the second train consists of 2 impulses and not 4, then at the end of these impulses the wipers **120** rest on the selector **4**. The relay **Ab** operates and over its contact **140ab** the winding II locks up in dependence on **141v1** of the slow-to-release relay **V1**.

The contact **41ab** in the circuit of the rotary magnet **Dkw2** is opened and hence this rotary magnet is removed beyond control by further impulses. These act exclusively on the numerical impulse acceptor of the exchange.

After selecting of the required branch set **AS7** the calling branch set transmits a final impulse train consisting of seven impulses by which the wipers of the indicating selector are set on the contact **17**. In this way the connecting signal for the required branch set **AS7** is determined which as is clear from Fig. 3 consists of a long negative impulse. The required branch set accordingly has the same connecting signal as the calling branch set **AS6**.

The relay **Kr3** on its operation has disconnected, the indicating selector **KW1**, operating on the connection of the calling branch set **AS6**, by opening the contact **142kr3** and over the contact **58kr3** has connected the wiper **122** of the marking selector **KW2**, in preparation. The relay **H** operates: -, relay **H**, contacts **138kr3**, **143v2**, wiper **121**, selector contact **17**, contact **144ba**, +, and at contact **202h** locks up in dependence on contact **171m**. The relay **G** is disconnected. The relay **J** is energized: +, contacts **145w**, **146h**, relay **J**, resistance **198**, -, and over the contact **26j** connects -120V to the conductor **1b**. At all branch sets the **B** relays operate and connect the condenser resistance arrangements to the conductor **1a**. Thus the relays **B6** and **B7** are connected at the branch sets **AS6** and **AS7**. Further the relay **BA** in the exchange is energized and by opening the contacts **144ba** removes the short circuit for winding II of relay **U1** which relay operates. The opening of contact **25i** results in the release of the relay **A**. The relay **V1** restores and at contact **59v1** connects the wiper **122** of the marking selector **KW2** which rests on selector contact **17** and is thus connected with - potential on the conductor **1a**. At all branch sets the condensers which are connected over one or two series resistances with the junctions **7** and hence with the conductor **1a**, are charged. At the required branch set **AS7** this charging circuit extends over the resistances **62**, **63**, the junctions **3**, **1**, the contact **64b7** and the condenser **Ko7** to earth.

In the calling branch set **AS6** the energizing of the relay **B6** also results in the opening of the speech circuit since the contact **109h6** is opened. The relay **S6** holds over its winding II which is connected to the conductor **1b** over the contact **147b6**.

At the same time as the relay **J**, relay **W** in the exchange is also energized: +, contacts **58p**, **69v1**, **148h**, relay **W**, -. At contact **145w** the relay **J** is disconnected. Since a long-impulse is necessary for connecting the branch set **AS7** the relay **J** must not release after the opening of contact **145w**. Its release is delayed by the discharge of the condenser **73** over its winding. The relay **E** controlling the charging and discharging of the condenser **73** is connected over its winding II: +, contacts **123ab**, **124v2**, wiper **120** and selector contact **17** of the marking selector **KW2**, contact **140j**, winding II of relay **E**, -. At con-

tact 12e it opens the discharging circuit of the condenser 13 and connects this parallel to relay J at contact 14e. After the discharge of the condenser 14e the relay J restores and among other things opens its contacts 60j and 149j and closes its contact 75j. The charging circuit over the conductor 1a is interrupted. The relay E is disconnected. Since it has a slow armature release the contact 11e is closed for a short period. A pre-discharging circuit is again set up for the condensers at the branch sets. The potential -120V maintaining the relays B at the branch set energized is connected after the closing of contact 25j over the contact 76e to the conductor 1b during the release period of the relay E. At the same time after the release of relay E there follows the disconnection of the current source -120V from the conductor 1b at contact 76e and the interruption of the pre-discharging circuit over the conductor 1a (at contact 11e).

When -120V is disconnected from the conductor 1b the B-relays in the branch sets restore. The release of relay B6 at the calling branch set is delayed however since its winding I is short-circuited at contact 113s6. The relay Ba in the exchange restores. The conductors 1a and 1b are switched through at the contacts 12ba and 78e.

As already described, in the discharging circuits of the condensers closed at the branch set after the release of the B-relay only the connecting relays at the branch sets AS75-8 operate, since the condensers of the branch set AS71-4 are discharged and connect their holding windings. At the calling branch set AS76 earth is disconnected from the winding II of relay R6 at contact 112s6. This relay cannot hold.

Of the connecting relays of the branch sets 5, 7 and 8 only the connecting relay R7 of the required branch set can hold its armature attracted. The winding II of this connecting relay R7 is connected to the conductor 1a. When the branch set AS76 which is also marked by a long negative impulse is not in its calling condition the winding II of its connecting relay R6 is applied to the conductor 1b. In order to maintain the relay R7 energized and hence to complete the connection of the branch set AS71 it is necessary in the exchange to connect the unearthing pole of an operating battery to the conductor 1a and earth to the conductor 1b. These operations are carried out as follows: the wiper 121 of the marking selector KW2 rests on contact 11. After the operation of relay Ba and the removal of the short circuit of winding II of relay U1 at contact 144ba this relay is energized. The relay U2 is connected at 89u1 and sets up a holding circuit over the winding I of relay U1 at contact 95u2. With attention to the calling branch set AS76 already connected to the party line a switching of the - pole from the conductor 1b to the conductor 1a and of earth from the conductor 1a to the conductor 1b cannot be carried out since the energized relay S6 at the branch set AS76 has its polarization reversed, which results in the restoration of its armature. The contacts 111s6 and 114s6 are opened and the branch set AS76 disconnected. Therefore at the conductor 1a the unearthing + pole of the battery is connected and earth to the conductor 1b. A change in the current direction over the party line does not occur.

The switching over from -60V on the conductor 1b to +60V on the conductor 1a takes

place in two stages. First +60V is connected over high resistance 94 and the contact 92u1 to the conductor 1a as well as earth over the high resistance 93 and the contact 91u1. Thereupon 5 there follows a disconnection of earth from the conductor 1a at contact 89u1 and of -60V from the conductor 1b at contact 33u1. If the slow relay U2 has also attracted its armature +60V is connected over the low resistance 98 and the contact 99u2 to the conductor 1a and earth over the low resistance 96 and the contact 97u2 at the conductor 1b. Microphone feeding current now flows over the party line at full strength.

The relay W completing the selecting impulse 15 has by its energization removed the short circuit for windings I and II of the differential relay X by opening the contacts 101w and 84w. The winding II of relay R7 of the branch set AS71 is therefore connected in the following holding circuit: +60V, resistance 98, contact 99u2, choke Dr1, contact 100y, winding I of relay X, contact 12ba, conductor 1a, branch set AS71, junctions 1, 5, winding II of relay R7, junctions 6, 4, contacts 82r7, 102s7, earth. After the release of the relay 20 B6 at the calling branch set the calling circuit exists over the latter: from the conductor 1a over junction 1, contacts nsi, hu6I, 114s6, relay S6, winding I, contacts 109b6, 111s6, junction 8, conductor 1b, contacts 25j, 78e, winding II of 25 relay X, contact 83y, relay A, contact 91u2, resistance 96, earth. The relay A operates. Further however, owing to the dissymmetry of the line in the exchange at the called branch set AS71 caused by the connection of the winding II of 30 relay R7 to the conductor 1a the difference relay X is energized since over its winding I stronger current flows than over its winding II. In this way the automatic periodic calling of the branch set AS71 is possible.

40 The contact 175x in the circuit of the relay V1 is opened. Since also the contact 35w is opened the closing of contact 36a cannot bring about an energization of the relay V1 by means of the corresponding bridge relay A so that a premature disconnection of the ringing current by disconnection of the relay W is avoided.

At contact 151w after the closing of contact 152ba a circuit is completed over the winding I of the relay Ab. The relay Ab among other 50 things disconnects at contact 125ab the holding circuit of the energized marking relays Kr2 and Kr3. The relay Kr1 is already restored during the selecting operation.

Over the contact 150w the relay W has completed a circuit for the call relay Rr. The relay Rr operates e. g. every 5 seconds by connecting the - pole over the time switch 5''.

The winding II of the connecting relay R7 of the selected branch set AS71 is applied to the conductor 1a. The bell of this branch set is connected to the conductor 1b. Ringing current is sent out from the exchange over these conductors over which the holding circuit for the previously energized connecting relay extends. 60 The connection for ringing current to one or other conductor is determined by the same relays U1, U2, which effect the connection of the unearthing pole of a central battery to the conductor 1a, or 1b. The relays U1 and U2 are energized when one of the branch sets AS71, 3, 5 or 7 is selected. When these are energized the contact 152u1 is opened and thus a short circuit of the winding I of the relay X during the call is avoided by the closing of the contact 153rr. The contact 154u2 is opened, so that accordingly 65 70

over the contact 155rr the alternating current source cannot be connected to the conductor 1a. By the closing of the contact 156u2 the short circuit of the winding II of relay X and by the closing of the contact 157u2 the application of ringing current to the conductor 1b is prepared. When the relay Rr operates under the control of the 5 seconds switch at contact 158rr it completes the short circuit of the winding II of relay X and at contact 159rr connects the alternating current source to the conductor 1b. The bell of the branch set ASt7 is operated on each connection of call current over the following circuit: call current source, contacts 159rr, 157u2, 78e, 25j, conductor 1b, junctions 8, 9, contacts 220r7, 15, bell, earth.

The differential relay X energized owing to the dissymmetry of the party line which is brought about at the branch set ASt7 prevents a premature energizing of the call relay M by opening of contact 160x.

When the subscriber of the called branch set ASt7 replies the winding I of the relay S7 is connected between the conductors 1a and 1b: conductor 1a, contacts nsi, hu7I, 161ru, winding I of relay S7, speaking apparatus, contacts 162b7, 163r7, junction 8, conductor 1b. The relay S7 operates and closes the contacts 164s7 and 165s7 parallel to the contacts 161r7 and 163r7. Further it opens the holding circuit over the winding II of relay R7 at contact 102s7. The dissymmetry of the line set up at this branch set after the selection is thus removed.

The result is that in the exchange the differential relay X restores and closes contact 175x. The relay VI can now operate: contacts 175x, 36a, relay VI, resistance 31, —. Further the contact 160x is closed. The relay PI operates after the energizing of relay VI: +, contacts 141vI, 173w, winding II of relay PI, —. Also the relay M is energized: +, contacts 141vI, 166w, 160x, relay M, —.

By the opening of contact 157m and closing of contact 168m + is connected over the contact 169c at the wiper 103 and thus to the meter Z6 of the calling branch set ASt6. The meter Z6 operates and registers the connection set up with the subscriber of the calling party line.

At contact 171m the holding circuit of the relay H is opened, this relay restores and at contact 117h closes the circuit for relay G which operates. By the opening of contact 28g the relay U2 is disconnected, restores and at contact 95u2 disconnects the relay U1. The release of the relays U1 and U2 results in the disconnection of the batteries whose + pole is unearthed and the connection of the normal operating batteries with unearthed — pole. The switching over from +60V on to earth at the contact 1a and from earth on to —60V at the conductor 1b takes place in two stages. At first by the opening of the contacts 91u2 and 99u2 the low resistances 96 and 98 are disconnected. There follows the closing of contacts 33u1, 92u1, whereby —60V is applied to the conductor 1b and earth to the conductor 1a, and thereupon the opening of contacts 91u1 and 92u1 and thus the final disconnection of +60V from the conductor 1a and earth from the conductor 1b.

Also in the switching operations there is no change in the current direction over the conductors 1a and 1b of the party line.

The release of the relay H also brings about the disconnection of the relay W by opening of the contact 148h. At the contacts 101w and 84w

the windings of the differential relay X are short circuited. The contact 173w in the circuit of the winding II of the relay PI is opened. The relay PI holds however over the parallel contact 117p1 and thus prevents an operation of the preselector VW by keeping the contact 175p1 open. At contact 117h the winding I of the relay G is connected.

When at the termination of a connection the subscribers of both branch sets ASt6 and ASt7 hang up their telephone instruments then the feeding bridge relay A in the exchange restores. At contact 48a the slow-to-release relay VI is short circuited and among other things interrupts the holding circuit of the relays Ab and PI by opening the contact 141vI. The relay PI restores quickly and at contact 44p1 closes a circuit for the rotary magnet Dkw2 of the marking selector KW2; —, rotary magnet Dkw2, contacts 113p, 20 44p1, 40vI, winding III of relay Ab, vertical off normal contact 171kkw2, interrupter RU, +. The relay AB is maintained energized by the current flowing over its winding III and prevents a release of the relay P during the release movement of the marking selector KW2 since the contact 176ab remains closed. When the marking selector KW2 reaches its normal position the principal off normal contact 171kkw2 is opened, the relay Ab restores and at contact 30 176ab interrupts the circuit of relay P. Further at contact 178ab is prepared the release circuit for the marking selector KW1. This is closed after the release of relay P and since the relay G still keeps its contact 179g open, extends as follows: —, rotary magnet Dkw1, contacts 45p, 44p1, 40vI, 178ab, relay G, winding II, rotary off-normal contact 180kkw1, interrupter RU, +. During the release movement the relay G remains energized over its winding II. When the marking selector KW1 reaches its normal position the principal off normal contact 180kkw1 is opened and the relay G restores.

On the release of the relay P the relay Y is also disconnected at contact 68p and sets back its contacts to normal. At contact 114p the circuit over the winding I of relay G is opened.

(3) Selection of the branch set ASt6 over the final selector LW

50 So long as the partly line is seized in the outgoing direction from a subscriber of a branch set the seizing over a final selector is prevented. At least one of the contacts 181g, 182an, 183a, 184p is opened so that when the test wiper 185 55 of the final selector sets on the required branch set e. g. ASt6 on its associated contact 6 the test relay Plw cannot operate.

If the partly line is free when the final selector sets on the junction of the branch set ASt6 the following test circuit is completed: +, test relay Plw, wiper 185, contact 6, resistance 187, contacts 181g, 182an, 183a, 184p, relay C, resistance 188, —. The test relay Plw carries out the usual switching operations in the final selector. The seizing relay C is connected over its contacts 189c in a holding circuit independent of the contacts of the connection 181g to 184g and at contact 190c the winding I of the relay PI to the wiper 56 of the marking selector KW1. Further it connects the cut-off relay Tr: +, contact 200c, rest contact 201 of the preselector VW, wiper 170, cut-off relay Tr, —. The relay Tr disconnects the calling bridge from the conductors 106 and 107 in known manner. At contact 169c the parallel path of the winding of the cut-off relay

Tr which contains the meter Z6 of the required branch set is opened so that on the energizing of the relay M occurring on the reply from the calling branch set and closing of contact 168m there is no energization of the meter Z6. The marking selector KW1 which on the call from a branch set is set by the marking presetting impulse train and brings about the connection of the calling branch set by connecting the particular connecting signal to the party line, serves also on the seizing of the party line over a final selector to connect the connecting signal of the branch set selected in the final selector. The contacts of the final selector are connected with the contacts of the contact bank passed over by the wipers 56 of the marking selector KW1.

The seizing relay C brings about the stepping on of the marking selector KW1 by closing the circuit for the driving magnet Dkw1 at contact 192c: —, rotary magnet Dkw1, contacts 45p, 44p1, 40v1, 178ab, 192c, vertical off-normal contact 191kkw1, interrupter RU, +. The marking selector moves forward by one step. The principal contact 191kw1 is opened and the principal contact 180kkw1 is closed. The circuit for the rotary magnet Dkw1 now extends over this contact and the contact 179g. When the wiper 56 of the marking selector KW1 rests on contact 6 and the relay P1 is energized: —, winding I of relay P1, contact 190c, wiper 56, contact 6 at 30 the marking selector KW1 and at the final selector LW, wiper 185, test relay Plw, +. The relay P1 operates and stops the marking selector KW1 by opening the contact 44p1.

The relays H and A are connected: —, relay H, contacts 193p1, 194p, + and —, resistance 34, contact 33u1, relay A, contacts 212y, 195p1, 196ba, + (earth). Over the contacts 36a and 35w or 175x the relay VI is connected, which energizes the relay P over contact 49v1. The relay J is energized: +, contacts 145w, 146h, relay J, resistance 198, —. In the manner already described —120V is connected over the contact 28j to the conductor 1b. The B-relays at all the branch sets and the relay Ba in the exchange operate. At contact 196ba the circuit over the relay A is opened. The relay A and hence also the relay VI restore.

At the branch sets the B-relays have connected the condenser resistance arrangements to the conductor 1a. Thus e. g. at the branch set AST6 the condenser Ko6 is connected over the contact 67b6, the junctions 1, 3 the resistance 66, 65 at junction 7 and hence to the conductor 1a. At the branch set AST7 the condenser is connected over the contact 64b7, the junction 1, 3, the resistances 63, 62 and the junction 7 at the conductor 1a. The condenser-resistance arrangements at all branch sets are controlled by means of the selecting current associated with the selected branch set AST6 by a long-impulse which also serves to select the branch set AST7.

Since the wiper 54 of the marking selector KW1 rests on contact 6, — is connected to the conductor 1a after the closing of contact 59v1. The condensers at all branch sets are charged in the manner described in section 1. Over the contact 69v1 since the contact 148h is closed, the relay W is energized, and at contact 145w opens the circuit of relay J. Since for the selecting of the branch sets AST6 (and also of the branch set AST7) a long impulse is necessary, the release of the relay J is delayed so that over the contact 57j and the wiper 20 of the

marking selector KW1 the energized relay E by opening of contact 72e and closing contact 74e connects the condenser 73 parallel to relay J. In the discharging circuit of condenser 73 the relay J remains energized. After the discharge of the condenser 73 it restores, opens the contacts 60j, 26j, 57j and closes the contacts 75j, 25j. During the release period of the relay E —120V is still connected over the contact 76e to the conductor 1b. During this period the pre-charging circuit for the condensers at the branch sets is also closed again over contacts 77e, 75j, 61ba. After the release of the relay E there follows the disconnection of —120V from the conductor 1b at contact 76b, the switching through of the conductor and at the same time the interruption of the pre-discharging circuit at the contact 77e. After the release of the relay Ba the conductor 1a is switched through at contact 12ba. By means of the pre-discharging circuit the condensers of the branch sets AST1 to 4 are discharged while the condensers of the branch sets AST5 to 8 have still a sufficient charge to energize a relay in a local discharging circuit. After the release of the B-relays at the branch sets the R-relays operate at the branch sets AST5 to 8 in the local discharging circuits of the condensers. Thus at the branch sets AST6 and AST7 the two relays R6 and R7 marked by means of the long-impulse, are energized. Both relays connect their holding windings II. Also at the branch sets AST5 and 8 not shown the windings II of the R-relays are connected.

The final connection of one of the two by the branch sets AST6 and AST7 selected by the same selecting current show connecting relays have their windings II differently connected to the party line one to the conductor 1a, the other to the conductor 1b, is dependent therefore on which of the conductors 1a or 1b has the un-earthed pole of the current source applied to it. For the completion of the connection of the branch set AST6 the un-earthed pole of the current source must be connected to the conductor 1b.

Over the contact 6 of the marking selector KW1 and the wiper 55 the relay U1 cannot be energized since its energizing circuit only extends over the contacts 1, 3, 5 and 7. The contacts of the relay U1 and hence also those of the directly dependent relay U2 remain in the normal position shown. Since the relay W has been energized as already described —60V is connected over resistance 34, contact 33u1, relay A, contact 83y, winding II of relay X, contacts 18e, 25j, to the conductor 1b, so that the relay R6 can hold its armature attracted. The relay R7 of the branch set AST7 restores since earth is connected to the conductor 1a in the exchange. The R-relay of the branch set AST5 whose winding II is also connected to the conductor 1a restores for the same reason as the relay R7 of the branch set AST7.

The winding II of the R-relay of the branch set AST8 is also connected to the conductor 1b as well as the winding II of the relay R8. However this relay can also not hold since as was mentioned earlier the holding winding is connected in similar manner to the holding winding II of the relay R7, i. e. the junctions 4 and 6 are connected with one another and the junction 5 is connected to junction 8. The current flowing over the winding II of the R-relay of the branch set AST8 therefore effects a reversal of the polarization of this relay so that it restores.

From the above it is clear that after the opera-

tion of the selecting devices at the branch sets consisting of condenser resistance arrangements by means of a selecting current of particular direction and duration a group of two branch sets (e. g. the group consisting of the branch sets ASt6 and 7) is selected. The start relay of each of these branch sets is connected to one conductor of the party line. In dependence on the selecting operation the current source in the exchange for maintaining energized the start relay of the required branch set is connected to that conductor of the party line to which the holding winding of this start relay is connected.

If the branch set ASt7 was to be selected, then a long — impulse would also be sent out. It could however then only hold the relay R7 at the branch set ASt7 since by the energizing of the relays U1 and U2 in the manner already described the inner + pole of a battery is connected to the conductor 1a and earth to the conductor 1b.

By the connection of the winding II of the relay R6 at the conductor 1b a dissymmetry of the party line is brought about at the selected branch set so that over the holding circuit of the relay R6 not only the relay A but also the relay X operates. Thus the automatic periodic calling of the branch set ASt6 is rendered possible. By the opening of the contact 175x the energizing of relay V1 is prevented. At contact 150w the call relay Rr is connected and under the control of the time switch 5' is energized for example every 5 seconds and applies call current to the conductor (1a) which does not extend the holding current to the connection relay. In the branch set ASt6 the bell rings.

When the called branch set ASt6 replies the relay S6 operates, closes the contacts 111s6, 114s6 and by disconnecting earth from the winding II of the relay R6 at contact 112s6 removes the dissymmetry of the party line. In the exchange therefore the relay X can no longer maintain its armature attracted but restores and closes the circuit for relay V1 at contact 175x which relay operates. The relay M is energized: +, contacts 141v1, 166w, 160x, relay M, —. The holding circuit of relay H is opened at 171m and by the release of this relay the relay W is also restored on the opening of contact 148h. The call relay Rr is disconnected and the windings I and II of the differential relay X are short-circuited at the contacts 101w and 84w.

The release of the relay H also results in the energizing of the relay G over its winding I: +, contacts 114p, 115v1, 116y, 117h, winding I of relay G, —. The relay G closes the contact 118g parallel to contact 115v1, opens the contact 179g and thus removes the short circuit over its winding II. The contact 181g in the seizing circuit is opened and at contact 202g the short circuit of the seizing relay is prepared.

At the termination of the connection the subscriber of the branch set ASt6 hangs up his receiver and the relays V1 and P restore. The circuit for the rotary magnet Dkw1 of the marking selector KW1 is closed. It extends as described earlier over the winding II of the relay G. The relay G since its contacts 184p, 183a, 182an and 202g are closed is short circuited and restores. At the contacts 190c and 189c the circuits for the relays P1 and C and the test relay Plw of the final selector are opened. The relay Plw restores and in the usual manner brings about the release of the incoming connecting path not shown.

II. EMBODIMENT ACCORDING TO FIGS. 4 TO 6

(1) The branch set ASt15 makes a call and is connected

5 The subscriber at the branch set ASt15 takes up his telephone. The switchhook contact hu15I is closed, the switchbook contact hu15II is opened. The call key Ta15 is pressed and the following call circuit completed: +, key Ta15, contacts 15b15, 16sp15, relay T15, switchhook contact hu15I, contact 17r15, junction 8, conductor 1a1, contacts 18w1, 19y1, 29ab1, 21h1, winding I of relay P2, winding I of relay An1, —.

10 The relay An1 in the exchange and T15 in the branch set ASt15 operate. The relay P2 in view of the high resistance of the relay T15 cannot operate. The relay An1 connects the relay J1: +, contacts 22kr13, 23an1, relay J1, resistance 24, —. At contact 25j1 the relay J1 disconnects 15 the conductor 1b1 from the repeater and connects —120V to it over the contact 26j1 and the resistance 27. The lamps at all the branch sets and the lamp Gla in the exchange light up. All B-relays operate and among others, the relay 20 Ba1 in the exchange, and at the branch set ASt15 and ASt16 shown, the relays B15 and B16 over the following path: —120V, resistance 27, contact 26j1, conductor 1b1, branch set ASt15; junction 9, lamp G115, relay B15, winding I, contact 33sp16, 34b15 (40t15 is open), 36s15, 36s15; 25 earth and at the branch set ASt16; junction 9, lamp G116, relay B16, winding I, contacts 28sp16, 29b16, or 30t16, 31s16, 32s16, earth.

30 At all branch sets not calling the closing of a call circuit is prevented by an operating B-relay thus at a branch set ASt16 by the opening of the contact 37b16 in series with the key Ta16.

35 At the calling branch set ASt15 earth is connected with relay T15 over the contacts 38t15 and 39b15, so that this relay also remains energized after the opening of contact 15b15. After the opening of contact 34b15 since the contact 40t15 is opened, the relay Sp15 operates in series with the winding I of relay B15. It opens the contact 16sp15 and closes the contact 41sp15.

40 The branch set ASt15 belongs to group I as is clear from Fig. 6. At this branch set the junctions 13 and 14 are connected. There follows accordingly during the release of the relay 45 T15 the momentary direct connection of earth over the contacts 39b15, 38t15, 41sp15, junctions 14, 13, contacts hu151, 17r15, junction 8 at the conductor 1a1 and thus to the call circuit. In the exchange the signal for the group I of the branch stations in the form of an earthed connection brings about the operation of relay P2 which locks up at contact 42p2 in a holding circuit over its winding II prepared at contact 43ba1. By the opening of the contact 44p2 and closing of the contact 45p2 there follows the first preparation of the circuit containing the meter Z15 of the calling branch stations ASt15.

45 After the opening of the contact 16sp15 in the branch set the relay T15 restores and the contact 38t15 is opened in the exchange the relay An1 restores. The relay W1 is energized: +, contacts 46kr13, 47an1, 48ba1, relay W1, —. At contact 18w1 it disconnects the windings I of relays An1 and P2 from the conductor 1a1. The contacts 49w1 and 50w1 are opened. Over the contact 51w1 the connection of the relay Ka to the conductor 1a1 and over the contact 52w1 the connection of the relay Kb at the conductor 1b1 are prepared. Further it connects the relay Y1: +, contacts 46kr13, 47an1, 48ba1, 53w1, 72ka, 73kb,

14ab1, relay Y1, —. The relay Y1 locks up together with the relay W1 over the contacts 15y1 and 76ab1. It closes a new holding circuit at contact 137y1 over the winding II of relay P2 and at the same time prepares over this contact the holding circuit to be explained later for the relays Ka, Kb, N and Ha. At contacts 11y1 and 78y1 the closing of the feeding and impulse bridge for the calling subscriber of the branch set AST15 is prepared.

By the opening of the contact 23an1 the relay J1 is disconnected. It restores and disconnects —120V from the conductor 1b1. The relay Ba1 restores. The conductor 1a1 is switched through at contact 61ba1 and the conductor 1b1 at the contacts 25j1, 58e1. In the branch stations the B-relays are disconnected.

At the calling branch set the relay Sp15 remains energized: earth, contacts 36s15', 35s15, relay Sp15, contact 54sp15, resistance 55, contacts 56b15, 57r15, junction 9, conductor 1b1, contacts 25j1, 58e1, 52w1, relay Kb, —. In this circuit the relay Kb cannot operate. The winding II of the relay R15 of the branch set AST15 is connected to the conductor 1a1 in series with the relay Ka in the following circuit: earth, contacts 59b15, 60sp15, junctions 4, 5, winding II of relay F15, junctions 7, 6, 8, conductor 1a1, contacts 61ba1, 51w1, relay Ka, —. Both relays R15 and Ka operate. In the exchange it is thus determined that the branch station belongs to group III.

The relay R15 opens at contact 57r15 the circuit for the relay Sp15, which restores and opens the contact 60sp15. The relay S15' is connected over the contact 62r15 in series with the winding II of the relay R15 and operates. It short circuits the relay R15 at contact 63s15'. So long as the relay R15 still holds its armature attracted earth is connected to the conductor 1b1 and brings about an energizing of the relay Kb determining that the branch AST15 belong to group VI, over the following path: earth, contact 68s15', junctions 12, 11, contact 69r15, junctions 10, 9, conductor 1b1, contacts 25j1, 58e1, 52w1, relay Kb, —.

The relay Ka is energized for the first time and thereupon the relay Kb. As a result the relay Ha is energized: +, contacts 10ka, 11kb, relay Ha, —. It has connected itself in a holding circuit over its contact 19ha. The connection of the meter associated with the calling branch set AST15 is further prepared at contact 82ha. The relays Ha, Ka, Kb, have further opened or closed the contacts 80ha, 81ha, 83ha, 84ka, 85ka, 86kb, 87kb, which do not serve to connect the meter Z15.

Since both relays Ka and Kb are energized on the call of the branch set AST15 both windings I and II of the relays N are connected. Their circuit extends over the contacts 88ka and 89kb and the holding windings II of the relays Ka and Kb. The relay N is a differential relay. It cannot operate when the current flows over both windings. In the meter connecting device the contacts 90n, 91n, accordingly remain closed and the contacts 92n, 93n remain open. The meter Z15 is connected over the contacts 82ha, 90n, 45p2.

By means of the control of the group determining devices in the exchange consisting of the relays P2, Ka, Kb, Ha and N by means of the characterizing signal for the group to which the calling branch set AST15 belongs it is determined that this branch set is included in the groups I, III and VI.

On the energizing of the relay Ka the holding circuit of the relay W1 provided with a slow armature release is opened at contact 12ka. The relay W1 restores and since in the meanwhile in the branch set AST15 the relay R15 has also restored and closed its contact 57r15, the microphone feeding circuit is closed. The relay S15' in view of its slow release holds its armature attracted for a certain period and thus the contact 64s15' and 65s15' are still closed. The feeding circuit extends as follows: + (earth), choke, Dr3, contacts 94u3, 95w2, 11y, 49w1, 61ba, conductor 1a1, contacts 17r15, hu151, 65s15', speaking apparatus (indicated by the microphone Mi) impulse contact ns15, relay S15, contacts 64s15', 56b15, 57r15, junction 9, conductor 1b1, contacts 25j1, 58e1, 50w1, 78y1, 96w2, 97u3, relay A1, —.

In the branch set AST15 the relay S15 operates and closes its contacts 66s15 and 67s15 in parallel to the contacts 64s15', and 65s15'. Further at contact 35s15 it opens the short circuit of winding II of relay S15', which however does not operate for the time being since the contact 54sp15 is opened and the lamp G15 has not lit up.

In the exchange the relay A1 operates. It opens the contact 98a1 and closes the contact 99a1, so that the relay V3 operates: +, contacts 99a1, 100w2 or 236x1, relay V3, resistance 101, —.

The relay V3 prepares the setting up of a circuit in such a manner that by the opening of the contact 102v3 and closing of the contact 103v3 it brings the rotary magnet Dkw of the marking selector KW under the control of the impulse contact 104a1. Further from the contact operations carried out by relay V1 there follow the further operations described above.

At the contact 105a1 the choke Dr4 is connected in bridge to the conductors 106 and 107 which extend to the preselector VW. In known manner the call relay of the preselector VW not shown operates and brings about the setting of the preselector on a free outgoing line. Parallel to the guarding and holding winding of the relay Tr1 shown is the meter Z15 of the calling branch set AST15 connected over the contacts 108w2, 109c1, 82ha, 90n, 45p2 in the same manner as a meter of an individual line subscriber.

(2) Connection of the branch AST15 and the branch set AST16

The subscriber of the branch set AST15 transmits an impulse train corresponding to the junction line 24226 of the branch set AST16. The first four digits of this train serve to mark the fact that this connection is required with a subscriber of the same party line. After this impulse train has had its effect a switching operation is performed in the exchange resulting in the release of the impulse acceptor which has been set and the completion of the connection is performed exclusively by apparatus on the party line. For this purpose the impulse trains operate on a discriminator on the party line namely on the marking selector KW.

The impulse trains sent out by the calling subscriber are transmitted from the relay A1 by means of contact 105a1 to the impulse accepting apparatus of the group and final selectors in the exchange. At the same time the setting of the marking selector KW, is performed so that on each release of the relay A1 the rotary magnet Dkw is connected: +, contacts 110y1, 111ab1, 104a1, 103v3, rotary magnet Dkw, —. On the coming into effect of the first impulse and closing of contact 98a1 the relay V4 is energized since

a short circuit of the windings I and II is removed at contact 99a1: +, contact 112v3, winding I and II of the relay V4, contacts 100w2, 236x1, 98a1, resistance 101, —. The relay V4 short circuits its winding II at contact 113v4 and this remains energized during the impulse train. The release of the relay V3 does not take place owing to the momentary closing of contact 98a1 occurring in each impulse to be transferred owing to the release period of this relay. The relay V4 among other operations opens its contact 114v4 and thus during each setting operation of the marking selector prevents the operation of the marking relay controlled over the wiper 115.

At the end of the first impulse train consisting of two impulses the marking relay Kr11 is energized over its winding I: +, contacts 116y1, 117ab1, 118a1, 114v4, wiper 115, contact 2, winding I of the characterizing relay Kr11, —. The relay Kr11 locks up over its winding h: +, contact 119y1, winding h, of the relay Kr11, contacts 120kr13, 121kr11, —. At contact 122kr11 it opens the connection between the selector contacts 5 and 6 over the contact 124kr11 connects the winding I of the marking relay Kr12 to the contact 6. The contact 123kr11 which is in series with the winding I of the relay Kr13 is opened.

By means of the second impulse train consisting of four impulses the marking selector KW is stepped on to the contact 6. At the closing of the contact 114v4 the marking relay Kr12 operates owing to the current flowing over its winding I. At contact 125kr12 it locks up over its winding h. It disconnects the connection between the selector contacts 7, 8 and 9, 10 at contacts 126kr12 and 127kr12, connects the reverse winding II of the marking relay Kr11 over its contact 128kr12 to the selector contact 8 and by closing contact 129kr12 prepares the operation of the marking relay Kr13 over the selector contact 10.

By means of the third impulse train consisting of two impulses the wipers of the marking selector KW are stepped on to the 8th contact. After the closing of contact 114v4 the circuit is completed over the reverse winding II of the relay Kr11; +, contacts 116y1, 117ab1, 118a1, 114v4, wiper 115, contacts 8, 128kr12, winding II of the relay Kr11, contacts 120kr13, 121kr11, —. The marking relay Kr11 restores. At contact 121kr11 it disconnects its two windings II and h simultaneously and at contact 123kr11 connects the winding of the marking relay Kr13 to the selector contact 10.

When the 4th impulse train (2nd impulse) has stepped on the wipers of the selector, the relay Kr13 operates. It closes its contact 130kr13 and thus completes a holding circuit over its winding h. At contact 131kr13 the connection of the selector contacts 14 and 15 is interrupted and at contact 132kr13 the connection of the relays E1 and the selector contacts 15 to 18 is prepared. The purpose of the relay E1 will be explained later.

Since the 4 impulses mark the connection with the subscriber of the calling party line there follows a release of the impulse acceptor connected in series which is set by the same impulse trains (group selector and final selector) in the exchange. The lost marking relay Kr13 to come into effect opens the talking conductor 107 at contact 133kr13. For this purpose the bridge relay arranged in one of the subsequent impulse acceptors restores and initiates the release operation in known manner.

When a connection is set up with a subscriber connected to a distant line then on the first of the impulse trains which does not correspond to the calling number of the calling party line, the marking selector KW is not set on the marking contact. There follows the immediate disconnection of the marking selector and its setting by the further impulse is thus prevented.

If the first impulse train consists not of 2 but of 3 impulses then after the closing of contact 114v4 the wiper 115 rests on the contact 3. The disconnecting relay Ab1 operates and locks up in a circuit extending over contacts 134y1 and 135ab1. At contact 117ab1 it disconnects the positive pole on the wiper 115.

After the selection of the party line the calling subscriber transmits a further impulse train corresponding to the junction number of the required subscriber (Ast16) consisting of six impulses which set the wipers of the marking selector KW on to the contact 16. After closing of contact 114v4 the relay E1 is energized. Thus the operation of the condenser resistance arrangements at the branch set is insured by means of the selecting current of definite polarity consisting of a long impulse.

This last impulse train corresponding to the calling number of the required branch set determines not only the duration of the selecting current operating the condenser resistance arrangement on the branch sets, but also its direction. As is clear from Fig. 3 the connection of positive is necessary for the selection of the branch set Ast16. The connection of — or +72V to the conductor 1a1 is therefore dependent on whether the relay An1 is energized or not in that —72V is only connected when the normal contact 137an1 is closed and +72V only when the operating contact 138an1 is closed.

Since the relay Kr13 is energized the relay Kr11 operates and the relay An1: +, contact 119y1, relay Kr11 winding h, contacts 140kr13, 141v4, 142ab1, wiper 143 contact 16, winding II of the relay An1, —. The contact 137an1 is opened and the contact 138an1 is closed. A connection of plus for operating the condenser resistance arrangement at the branch set is thus ensured.

The contact 141v4 in parallel to the contact 145kr11 is closed. The closing of the contact 146kr11 in series with the winding I of the relay Ab1 is for the time being without importance. Over the contact 147kr11 since the contact 148kr13 is closed, the relay J1 is energized and opens the contact 25j1 and closes the contact 26j1. —120V is thus connected to the conductor 1b1. The lamp Gla in the exchange and at the branch sets for example G1/5 and G1/6 in the branch sets Ast15 and Ast16 shown are lit up. The relay Ba1 in the exchange operates and the B relays at all the branch sets. At the calling branch set Ast15 since the contact 35s15 is opened the relay S15 is also energized over its winding II and operates the contacts shown in the drawings in their normal positions. Since the circuit over the relay S15 and the talking apparatus is opened at the contact 56b15 the relay S15 restores. At all branch sets the B relays have connected the condenser resistance arrangements controlled by the selecting current. Thus at the branch set Ast16: earth, condenser Ko16, contacts 158b16', 157s16' connection 1, 3, resistance 256, 156, connection 8, conductor 1a1. At the calling branch set a similar branch of the conductor 1a1 is not completed over the con-

denser resistance arrangement since the contact 162s15' is opened.

In the exchange the relay W2 is energized: +, contact 149ba1, winding I of the relay W2, wiper 150, selector contact 16, resistance 151, —, and locks up over its winding II: +, contacts 183y1, 184w2, winding II, resistance 186, —. The short circuit for the winding I and II of the relay XI is removed at contacts 95w2 and 96w2. Further the contact 6ba1 is opened and the contact 152ba1 is closed.

The relay A1 restores by the opening of the contact 25j1 and opens the short circuit for the relay V2 so that this operates momentarily. The relay V3 restores. During the time in which the relay V4 holds its armature attracted the winding I of the relay Ab1 is energized: +, contact 134y1, 153v4, 145kr11, winding I of the relay Ab1, —. The relay Ab1 connects itself in a holding circuit independent of contact 153v4 by closing the contact 135ab1. At contact 142ab1 the previously described circuit extending over the winding h of relay Kr11 is interrupted. The relay Kr11 restores and disconnects the relay J.

So long as the relay J1 holds its armature attracted after the energizing of the relay Ba1, +72V is connected over resistance 138, contacts 139an1, 154kr13, 155j1, 152ba1, to the conductor 1a1. With the exception of a calling branch station AST15 at which as already mentioned the contact 162s15' is opened, the condensers are charged at all branch sets. For example at the branch set AST16 shown, over junction 8, resistances 156, 256, junction 3, 1, contacts 157s16', 158b16, condenser Ko16, earth.

For the selection of the branch set AST16 and also the branch set AST15 a long positive impulse is necessary. Since the branch set AST15 is already in the calling condition there is at this branch set no operation of the condenser resistance arrangement. If this branch set is also in its normal position then as detailed in section 3 the condenser resistance arrangements at this branch set are operated so that the connection of the branch set AST15 is prepared together with the connection of the branch set AST16. The final connection is then dependent on the conductor to which the necessary current source in exchange for maintaining the connecting relays energized is connected, i. e. 1a1 or 1b1, since the winding II of the relay R15 is connected to the conductor 1a1 and the winding II of the relay R16 to the conductor 1b1.

Since a long positive impulse is to be sent out the relay J1 must not restore at the opening of contact 147kr11 as a short positive impulse only marking the branch set AST11 or AST12 would then be transmitted. The condensers of the branch set AST11 or AST14 are completely charged and not the condensers of the branch set AST15 to AST18. At the branch set AST15 the charging circuit is opened in known manner at contact 162s15'.

The delay in the release of the relay J1 serves to bring about the energization of relay E1 after the last impulse train sent out from the calling subscriber, which, relay opens the charging circuit of the condenser 220 at contact 218e1 and connects this over contact 219e1 parallel to relay J1. At the opening of the contact 147kr11 the condenser 220 discharges over relay J1 which holds its armature attracted during the flow of discharge current. It only restores after the discharge of the condenser 220. The prolonged connection of + to the conductor 1a1 effects a com-

pletion discharge of the condensers at all branch sets at which the condenser resistance arrangements are connected.

After the release of the relay J1 a predischarging impulse is completed over the conductor 1a1, for the discharge of the condensers at the branch sets selected by means of a selecting current of short duration. The contacts 155j1, 26j1, 217j1 are opened and the contacts 159j1, 25j1 are closed. During the release period of the relay E1, disconnected at contact 217j1, —120V is connected over the contacts 221e1 and 25j1 to the conductor 1b1. The B relays all remain energized. Over the contacts 160e1, 159j1 and 152ba1 earth is connected to the conductor 1a1.

After the release of the relay E1 the condensers of the branch sets AST11 to AST14 are completely discharged while the condensers on the branch sets AST16 to AST18 still retain a charge which is sufficient to operate connecting relays in local discharge circuits e. g. the relay R16 of the branch set AST16.

The disconnection of —120V from the conductor 1b1 by the opening of the contact 221e1 results in the release of the B relays in the branch sets and of the relay Ba1. At contact 6ba1 the conductor 1a1 switches through and the conductor 1b1 at contacts 25j1, 58e1.

At the calling branch set AST15 the relay B15 restores slowly since its winding II is short circuited by the contact 151s15'. The relay S15' however has a longer armature release than the relay B15 so that the relay S15 after closing contact 56b15 can operate over the contacts 64s15' and 65s15 still closed in the feeding circuit again completed in the exchange over the relay A1.

At the branch stations AST16 to 18 the condensers discharge over the winding I and the R relays of this branch set e. g. at the branch AST16 and the condenser Ko16 of contact 173b16 and winding I of the relay R16. The holding winding II of the R relays are connected to the party line. At the branch set AST16 winding II of the relay R16 is connected to the conductor 1b1 over the following path: earth, contacts hu16II, 274r16, junction 4, 5, winding II of the relay R16, junction 7, 6, 9, conductor 1b1. At the branch set AST18 as is clear from Fig. 3 the holding winding II is also connected to the conductor 1b1, while the holding winding of the relay at the branch set AST17 is connected with conductor 1a1. At the last mentioned branch set the R relays are disconnected as after the switching through of the party line earth is connected over choke Dr3 to the conductor 1a1 and accordingly the relay can no longer maintain its armature attracted. Also at the branch set AST18 the R relay is disconnected although the holding winding is connected with the conductor 1b1 since the holding winding is in the opposite direction at this branch set to the holding winding of branch set AST16 since the junction 6, 7, and 4, 5 are not connected with one another but as is shown in Fig. 3 the junction 4, 7 and 5, 6 are. The R relay of the branch set AST18 has its polarization reversed and restores.

Only at the branch set AST16 does the relay R16 remain energized since the holding current over the winding II is the same as the current over the winding I. The reversal of the polarization does not take place.

By the connection of the holding winding II of the relay R16 the discriminator is set up in the party line. This has the result that in the

exchange after the switching through of the conductors for the party line differential relay **X** in the feeding bridge of the subscribers operates in the holding circuit of relay **R16**. It opens the contacts **175x1** and **236x1**. A short circuiting of the winding II of the relay **W2** is prevented during the energization of the calling relay **Rr1**. Moreover the relay **V3** cannot operate although contact **99a1** is closed since the contact **100w2** is also opened. The contact **176v3** in series with the contacts **175x1** and **185rr1** remains open. A short circuit of the winding II of the relay **W2** is also prevented in this position by the closing of contact **185rr1**.

There follows the calling of the selected branch station **AST16**. The relay **Rr1** is energized at definite time intervals for example every 5 seconds: —, relay **Rr1**, contact **161w2**, call switch **5''**, and closes contacts **168rr1** and **170rr1**. Over the first mentioned contact ringing current is connected to that conductor in the present case **1a1**, over which the holding current for the relay **R16** of the selected branch set **AST16** does not extend. The contact **170rr1** is connected in series with contact **169u3** and short circuits the winding I of the relay **X1**. The ringing current takes the following path: A. C. source, contact **168rr1**, condenser, contacts **171u3**, **165w2**, **77y1**, **49w1**, **61ba1**, conductor **1a1**, branch set **AST16**, junction **8**, **10**, contact **174r16**, bell, earth.

When the called subscriber at the branch set **AST16** takes up his hand instrument the short circuit for the winding I of the relay **S16'** is removed at contact **172hu16II**. It operates and closes its contacts **176s16'**, **177s16'**, **178s16'**. At contact **176s16'** the winding II of the relay **R16** is short circuited and at contacts **177s16'** and **178s16'** the connection of the talking apparatus in bridge across the conductors of the party line is prepared.

The relay **R16** restores and closes the contact **179r16**. Over this contact and the contacts **177s16'** and **178s16'** the relay **S16'** holds its armature attracted after the opening of the contact **274r16** in view of its slow to release properties, the talking apparatus is in series with the relay **S16** in the following connection bridging the party line: conductor **1a1**, junction **8**, contacts **180r16**, **hu16I**, **178s16'**, operator's equipment impulse contact **ns16**, relay **S16**, contacts **177s16'**, **181b16**, **179r16**, junction **9**, conductor **1b1**. The relay **S16** operates and maintains the circuit described above by closing contacts **182s16** and **183s16**, parallel to contacts **178s16'** and **177s16'** after the release of relay **S16'**.

By the opening of contact **274r16** the discriminator in the party line at the selected branch set is removed. Then as a result in the exchange differential relay **X1** restores. Over the contact **236x1** the relay **V3** operates and closes contact **176v3**. On the next energization of the relay **Rr1** the holding winding II of the relay **W2** is short circuited over the contacts **175x1**, **185rr1**, **176v3**. The relay **W2** restores and opens the circuit of the relay **Rr1**. At the same time at the contacts **95w2** and **96w2** there follows the short circuiting of the windings I and II of the differential relay **X1** so that during the conversation over the microphone feeding circuit only the relay **A1** and the choke **Dr3** are connected.

At contact **234v3** the relay **Y1** is further held after the opening of contact **213w2**.

The release of the relay **X1** on the reply of the subscriber of the called branch set **AST16** is the reply signal which results in the connection of

the meter **Z15** and the calling branch set in the following local circuit: +, contacts **187v3**, **188x1**, **189w2**, **199cl**, meter **Z15**, contacts **82ha**, **90n**, **45p2**, —. On the release of the relay **W2** the contact **189w2** is opened and thus the circuit of the meter **Z15** is interrupted again.

When at the end of the conversation the subscriber of the branch sets **AST15** and **AST16** hangs up his apparatus the relays **A1** and **V1** restore. The relay **V1** is the retrace relay and sets back the apparatus in the exchange to normal and closes the circuit over the rotary magnet **Dkw** at contact **102v3** which is completed after the release of relay **Y1**: —, magnet **Dkw**, contacts **102v3**, **138y1**, **265n1**, winding II of the relay **Ab1**, contact **129kckw**, interrupter **Unt**, +. In the rest position of the marking selector the contact **139kckw** is opened. The selector is stopped. The relay **Ab1** maintained energized during the release operation of the selector **KW** prevents the party line from being seized so long as all the apparatus is not in its normal condition, since the contact **194ab1** in the incoming ceasing conductor is open.

25 In the branch sets **AST15** and **AST16** the relays **S15** and **S16** restore.

For the final connection of a branch set determined by the selecting current of either direction or duration, in contrast to the embodiment I (Figs. 1 to 3) in the present embodiment II (Figs. 4 to 6) the unearthed — pole of the normal operating battery with its positive pole earthed is connected in dependence on the selecting operation in the exchange through to the conductor **1a1** or conductor **1b1**. The current direction is hereby also reversed.

When the subscriber of the branch set **AST16** has made a call and set up a connection with the subscriber of branch set **AST15** then in the exchange by means of the relay **U3** the — pole of the battery is switched over from the conductor **1b1** to the conductor **1a1** so that the relay **R15** whose winding II is connected to the conductor **1a1** is maintained energised. This current reversal does not result in the disconnection of the calling branch set **AST16** since at this branch set the relay **S16** energises for the initiating of the call and restores during the conversation. During the connection of the branch set **AST15** its repeated energisation by the current of opposite direction flowing over the line is ensured by means of the auxiliary relay **S16'** which closes the energising circuit for relay **S16** at contacts **177s16'**, **178s16'**. A special source of opposite polarity to the normal earthed operating battery is not necessary.

(3) The branch set **AST15** is selected over the final selector **LW**

60 After the setting of the test wiper **190** of the final selector **LW** on the contact **15** of the branch set **AST15** the following seizing circuit is completed: +, test relay **Plw** of the final selector, wiper **190**, contact **15**, resistance **191**, contacts **192an1**, **193w1**, **194ab1**, **195y1**, relay **C1**, resistance **196**, —. The test relay **Plw** carried out the known switching operations in the final selector. The seizing relay **C1** locks up over its contact **197cl** in a holding circuit independent of the contacts **192an1** to **195y1**, connects at contact **198cl** the winding III of the relay **N** serving as a test relay for incoming traffic at the wiper **199** of the marking selector **KW** and over contact **200cl**, the contact **202** and wiper **203** of the pre-selector **VW** energises the contact of relay **Tr1**

which operates. At contact 206c1 conductor 107 is opened and thus an operation of the pre-selector VW on the closing of contact 105a1 occurring later is prevented.

At contact 204c1 the circuit is completed for the rotary magnet Dkw of the marking selector: —, rotary magnet Dkw, contacts 102v3, 136ab1, 204c1, off-normal contact 140kkw, interrupter Unt, +. On the first rotary step of the selector the off-normal contact 140kkw is opened and the off-normal contact 139kkw is closed. The rotary magnet Dkw is now energised in the following circuit: —, rotary magnet Dkw, contacts 102v3, 138y1, 205n, 305abl, off-normal contact 139kkw, interrupter Unt, +. The marking selector operates until the wiper 199 rests on contact 15 which is connected with the contact 15 of the final selector. The following test circuit is then completed: winding III of the relay N, contact 198c1, wiper 199, contact 15 on the marking selector KW and on the final selector LW, wiper 190, test relay Plw, +. The relay N then operates and opens the circuit of the rotary magnet Dkw. Further the relay A1 is energised: earth, contact 207y1, 208n, relay A1, —. At contact 99a1 the relay V3 is connected.

By the setting of the marking selector KW the polarity and the duration of the necessary selecting current for connecting the required branch station is determined. For the selection and hence for the connection of the branch station a long positive impulse is necessary which requires the energising of the relays An1, Kr13, J1 and Ba1. The relay N connects the relay Kr13, +, contact 209n, 210kb, 211ka, relay Kr13, winding h, —. It closes its contacts 154kr13 in the selecting circuit and 140r13 in the circuit of winding h of relay Kr13. This operates in series with the relay An1 (winding II): +, contacts 209n, 210kb, 211ka, 130kr13, winding h of the relay Kr13, contacts 140kr13, 141v4, 142abl, wiper 143, contact 15 of the marking selector KW, relay An1, winding II, —. The relay An1 disconnects: —72V at contact 137an1: at contact 139an1: +72V. Over the contacts 148kr13 and 147kr13 the relay J1 energised and at contact 26j —120V is connected to the conductor 1b1. As described the relay Ba1 is operated over the B relays at the branch stations. The condensers at all branch stations are connected for charging to the conductor 1a1. The relay Ba1 opens the contact 61ba1 in the conductor 1a1 and connects +72V to the outgoing conductor. The condensers at the branch sets are charged.

In the exchange since the wiper 150 rests on contact 15 the relay W2 is energised in series with relay U3: +, contact 149ba1, winding I of the relay W2, wiper 150, contacts 15, 212u3, relay U3, —.

Over the winding II of the relay W2 the holding circuit is completed: +, contacts 183y1, 184w2, winding II of the relay W2, resistance 186, —. The relay W2 closes the holding circuit for the relay U3 at contact 215w2 extending over contact 216u3.

The relay W2 energises the relay Y1 over contact 213w2 and this relay operates. At contact 17y1 and 18y1 the feeding bridge is prepared. The relay E1 is energised: +, contacts 116y1, 117abl, 118a1, 114v4, wiper 115, contacts 15, 132kr13, 207j1, relay E1, —. At contact 207y1 the relay A1 is disconnected and restores and at contact 99a a circuit over the relay V3 is opened. The relay V4 operates momentarily and brings about an energisation of the relay E1: +, con-

tacts 134y1, 153v4, 146kr11, winding I of the relay A1, —. The relay E1 opens contact 218e1 and over contact 219e1 connects the charged condenser 220 parallel to the relay J1. Further the contact 58e1 is opened and over the contact 221e1 the connection of —120V to the conductor 1b1 is prepared after the release of the relay J1.

The relay A1 connects itself in the holding circuit over the contacts 135abl and 134y1. At contact 142abl it opens the circuit over the winding I of the relay An1 and h of the relay Kr11. In the first place only the relay Kr11 is restored since the relay An1 is maintained energised over its winding I: +, contacts 222ba1, 223w2, 224an1, winding I of the relay An1, —.

The release of the relay Kr11 results in the disconnection of the relay J1. The relay J1 is however only momentarily held by the discharge current of the condenser 220. Thus a positive selecting current of long duration is transmitted over the conductor 1a1 and results in the complete charging of the condensers at all branch sets. After the discharging of the condenser 220 the relay J1 restores, closes the contacts 159j1, 25j1 and opens the contacts 155j1, 26j1 and 207j1. At the last mentioned contact the relay E1 which has a slow armature release is disconnected. After the closing of contact 25j1 therefore —120V remains connected over contact 221e1 during the release period of relay E1 at the conductor 1b1. In the time between the release of relay J1 and relay E1 earth is connected over the contacts 160e1, 159j1 and 152ba1. Thus the pre-discharging circuit for the condensers at all branch stations is completed.

The condensers of the branch sets ASt11 to 14 which are already completely charged by a short-circuiting current are completely discharged since at these branch sets the junctions 1 and 2 are connected with one another. At branch sets ASt15 to ASt18 the junctions 1 and 3 are connected with one another. In the charging and pre-discharging circuits two resistances e. g. 225 and 226 are connected to the branch set ASt15. These condensers are only completely charged by a long impulse and only partially discharged in the predischarging circuit.

After the release of the relay E1 in the exchange and after the opening of the predischarging circuit the condensers of the branch sets ASt15, ASt18 still have sufficient charge to be able to operate relays in local discharging circuits.

The release of the relay E1 in the exchange also results in the disconnection of —120V from the conductor 1b1. The relay Ba1 and the B relays at all branch sets restore. At the branch sets ASt11 to ASt14 the condensers are already discharged and the R relays are not energised. At the branch sets ASt15 to ASt18 the R relays operate in the discharge circuit and connect their winding II to the party line. At the branch sets ASt15 and ASt11 these windings are connected to the conductor 1a1 and at the branch set ASt16 and ASt18 to the conductor 1b1.

Therefore only the relay R15 at the branch set ASt15 must remain energised.

By means of a long positive impulse both branch sets ASt15 and ASt16 are selected. Which of these two branch sets is finally connected depends on the conductor at the exchange to which the unearthed, — pole of the operating battery is connected.

The winding II of the relay R15 of the required

branch set is connected to the conductor $1a1$ and the — pole of the operating battery normally to the conductor $1b1$. For the final connection to the branch set $AS15$ therefore the switching over of the negative pole to the conductor $1a1$ is necessary. This switching over is carried out by the relay $U3$ on the closing of contact $228u3$, $229u3$ and opening of the contacts $94u3$, $97u3$.

After the switching through of the conductors $1a1$ and $1b1$ the following circuit is completed: —, relay $A1$, contact $229u3$, winding I of the relay $X1$, contacts $11y1$ $49w1$, $61ba1$, conductor $1a1$, branch set $AS15$, junctions 8 , 6 , 7 , winding II of the relay $R15$, junctions 5 , 4 , contacts $62r15$, $hu1511$, earth.

At the same time current flows over the winding II of the R relays of the branch set $AS17$. Since this winding is oppositely directed to that of the branch set $AS15$ and the junctions 5 , 6 , and 7 , 4 , are connected with one another there follows a reversal of poles which then results in the release of the R relays.

The R relays of the branch sets $AS16$ and $AS18$, seizing winding II are connected to the conductor $1b1$ and restore.

The difference relay $X1$ seized winding I is connected in the holding circuit of the relay $R15$ and operates together with the relay $A1$. It opens contact $236x1$ and thus prevents the energising of the contact $99a1$. The contact $175x1$ is opened. At contact $167w2$ the called relay $Rr1$ is connected which in dependence on a time switch for example is energised every 5 seconds and over its contact $168rr1$ connects ringing alternating current source. Since the relay $U3$ is energized the contact $171u3$ opens and the contact $230u3$ closes the ringing current flows over the conductor $1b1$ which is not used to hold relay $R15$ of the required branch set and to the branch set $AS15$ over junction 10 , 9 the contact $69r15$ to earth.

During the sending of ringing current the winding II of the difference relay $X1$ is short-circuited at contacts $231u3$, $232rr1$ and a short circuit of the winding I of the relay $X1$ is prevented since the contact $169u3$ is opened.

When the called station replies then on the taking up of the hand instrument the short circuit of the winding I of the relay $S15'$ extending over the switch hook contact $hu1511$, is removed. Relay $S15'$ operates and short circuits the winding II of $R15$ at contact $62s15'$. Further it closes the contacts $64s15'$ and $65s15'$. The relay restores by opening the contact $62r15$ removes the dissymmetry of the line set up after the selection of the branch set $AS15$ and closes the contact $57r15$. In view of this slow armature release the relay $S15'$ holds its armature attracted for a short period after the opening of the contact $62r15$ so that relay $S15$ is connected across the conductors $1a1$ and $1b1$ of the party line and operates: conductor $1a1$, junction 8 , contact $17r15$, $hu151$, $65s15'$, operator's equipment, impulse contact, $ns15$, relay $S15$, contacts $64s15'$, $56b15$, $57r15$, junction 9 , conductor $1b1$. The relay $S15$ closes the contacts $64s15'$ and $65s15'$ parallel to the contacts $66s15$ and $67s15$. The disconnection of earth from the conductor $1a1$ and removal of the discriminator of the party line results in the connection of the difference relay $X1$, in the exchange. Current flows over both neighbouring windings I and II. Over contact $236x1$ the relay $V3$ is connected. The contact $176r3$ is closed. The winding II of the relay $W2$ is short-circuited on the next closing of con-

tact $185rr1$. The relay $W2$ restores, disconnects the call relay $Rr1$ and at contacts $95w2$ and $96w2$ short circuits the windings I and II of the difference relay $X1$. The relay $U3$ is maintained energised at $245v3$.

A metering of the incoming traffic is prevented by the opening of contact $109c1$ of the seizing relay $C1$ energised throughout the connection.

After the termination of the connection and hanging up of the hand instrument at the subscriber's set $AS15$ the relays $A1$ and $V1$ restore and bring about the release of the connecting apparatus. Since the contact $233ab1$ is closed after the relay $Y1$ is disconnected by opening of

15 the contact $234r3$ the relay $C1$ is short circuited over the series contacts $235a1$, $233ab1$, $195y1$. It restores and at contact $198c1$ opens the circuit over the winding III of the relay N and the relay Plw of the final selector. The latter restores and brings about the release of the final selector, not shown. The relay N closes the circuit over the rotary magnet Dkw of the marking selector at contact $205n1$. In this circuit described earlier is the winding II of the relay $Ab1$. This relay 20 restores when the marking selector has reached its normal position and at contact $194ab1$ removes the relay $C1$ and contact $194ab1$ closes the incoming seizing conductor.

What is claimed is:

30 1. In a telephone or like system, an exchange, a party line terminating at the exchange, a plurality of stations on said line each having a device normally disconnected from the line, means at each of said stations for transmitting digits over the line to the exchange, means at the exchange controlled by a plurality of successive digits received over the line from one of said stations for at times transmitting over said line a station selecting impulse depending in duration upon said digits, and means at each station for connecting the device at that station to the line responsive only to the receipt of a selecting impulse of a particular duration.

2. In a telephone or like system, an exchange, 45 a party line terminating at the exchange, a plurality of stations on said line each having conversational equipment, means at each station normally disabling the conversational equipment thereat, means at each station for transmitting digits over the line to the exchange, means at the exchange controlled by a plurality of successive digits received over the line from one of said stations for at times transmitting over said line a station selecting impulse depending in duration upon said digits, and means at each station for rendering the disabling means thereat ineffective responsive only to the receipt of a selecting impulse of a particular duration.

3. In a telephone or like system, an exchange, 60 a party line terminating at the exchange, a plurality of stations on said line each having a device normally disconnected from the line, means at each of said stations for transmitting digits over the line to the exchange, means at the exchange controlled by a plurality of successive digits received over the line from one of said stations for at times transmitting over said line a station selecting impulse depending in polarity and duration upon said digits, and means at each station for connecting the device at that station to the line only upon the receipt of a selecting impulse of a particular polarity and duration.

4. In a telephone or like system, an exchange, 75 a party line terminating at the exchange, a plu-

rality of stations on said line each having conversational equipment, means at each station normally disabling the conversational equipment thereat, means at each station for transmitting digits over the line to the exchange, means at the exchange controlled by a plurality of successive digits received over the line from one of said stations for at times transmitting over said line a station selecting impulse depending in polarity and duration upon said digits, and means at each station for rendering the disabling means thereat ineffective only upon the receipt of a selecting impulse of a particular polarity and duration.

5. In a telephone or like system, an exchange, a party line terminating at the exchange, a plurality of stations on said line each having normally disabled signalling equipment, means at one of said stations for transmitting over the line to the exchange impulses characterizing any other station on said line, means at the exchange controlled by said impulses for transmitting a station selecting impulse, said station selecting impulse comprising a single uninterrupted impulse of direct current depending in duration upon the impulses received from said one station, and means controlled over the line by said station selecting impulse for conditioning the signalling equipment at the characterized station only for operation.

6. In a telephone or like system, an exchange, a party line terminating at the exchange, a plurality of stations on said line each having normally disabled signalling equipment, means at one of said stations for transmitting over the line to the exchange impulses characterizing any other station on said line, means at the exchange controlled by said impulses for transmitting a station selecting impulse of variable polarity and duration, the polarity and duration of said station selecting impulse depending upon the impulses received from said one station, and means controlled over the line by said station selecting impulse for conditioning the signalling equipment at the characterized station only for operation.

7. In a telephone or like system, a party line, a plurality of stations on said line each having a device normally disconnected from the line, means at each of said stations for connecting the device at that station responsive only to the receipt over the line of an impulse of a particular polarity and duration, and means for first transmitting over the line an impulse of a certain polarity and duration to operate the means at one of said stations and for then transmitting over the line an impulse of the same polarity and a different duration to operate the means at another of said stations, thereby to cause the devices at said two stations to be connected to the line concurrently.

8. In a telephone or like system, a party line, a plurality of stations on said line each having a device normally disconnected from the line, means at each of said stations for connecting the device at that station responsive only to the receipt over the line of an uninterrupted impulse of a particular polarity and duration, and means for first transmitting over the line an uninterrupted impulse of a certain polarity and duration to operate the means at one of said stations and for then transmitting over the line an uninterrupted impulse of a different polarity but the same duration as said first impulse to operate the means at another of said stations, thereby

to cause the devices at said two stations to be connected to the line concurrently.

9. In a telephone or like system, a party line, a plurality of stations on said line each having a device normally disconnected from the line, means at each of said stations for connecting the device at that station responsive only to the receipt over the line of an uninterrupted impulse of a particular polarity and duration, and means for first transmitting over the line an uninterrupted impulse of a certain polarity and duration to operate the means at one of said stations and for then transmitting over the line an uninterrupted impulse of a different polarity and a different duration to operate the means at another of said stations, thereby to cause the devices at said two stations to be connected to the line concurrently.

10. In a telephone or like system, a party line, a plurality of stations on said line each having normally disabled signalling equipment, means for first transmitting over the line an impulse of a certain polarity and duration and for then transmitting over the line an impulse of the same polarity but a different duration, means controlled over the line by said first impulse for conditioning signalling equipment at one of said stations only for operation, and means controlled over the line by said second impulse for conditioning signalling equipment at another of said stations only for operation, thereby to cause the signalling equipment at said two stations to be conditioned concurrently.

11. In a telephone or like system, a party line, a plurality of stations on said line each having normally disabled signalling equipment, means for first transmitting over the line an impulse of a certain polarity and duration and for then transmitting over the line an impulse of a different polarity but the same duration, means controlled over the line by said first impulse for conditioning signalling equipment at one of said stations only for operation, and means controlled over the line by said second impulse for conditioning signalling equipment at another of said stations only for operation, thereby to cause the signalling equipment at said two stations to be conditioned concurrently.

12. In a telephone or like system, a party line, a plurality of stations on said line each having normally disabled signalling equipment, means for first transmitting over the line an impulse of a certain polarity and duration and for then transmitting over the line an impulse of a different polarity and a different duration, means controlled over the line by said first impulse for conditioning signalling equipment at one of said stations only for operation, and means controlled over the line by said second impulse for conditioning signalling equipment at another of said stations only for operation, thereby to cause the signalling equipment at said two stations to be conditioned concurrently.

13. In a telephone or like system, an exchange, a party line terminating at the exchange, a plurality of stations on said line each having normally disabled signalling equipment, means at each of said stations for initiating calls, means at the exchange responsive to the operation of said means at one of the stations for conditioning certain of said signalling equipment at that station for operation, means for transmitting over the line from said one station impulses characterizing any other station on said line, means at

the exchange for receiving said impulses and transmitting over the line an uninterrupted station selecting impulse dependent in duration upon the received impulses, and means operated by said selecting impulse for conditioning certain of said signalling equipment at the characterized station for operation.

14. In a telephone or like system, an exchange, a party line terminating at the exchange, a plurality of stations on said line each having normally disabled signalling equipment, means at each of said stations for initiating calls, means at the exchange responsive to the operation of said means at one of the stations for conditioning certain of said signalling equipment at that station for operation, means for transmitting over the line from said one station impulses characterizing any other station on said line, means at the exchange for receiving said impulses and transmitting over the line an uninterrupted station selecting impulse dependent in duration upon the received impulses, means controlled by said selecting impulse for conditioning certain of said signalling equipment at the characterized station for operation, and other means controlled by said selecting impulse for maintaining the signalling equipment at said one station conditioned for operation.

15. In a telephone or like system, an exchange, a party line terminating at the exchange, a plurality of stations on said line each having normally disabled signalling equipment, means at each of said stations for initiating calls, means at the exchange responsive to the operation of said means at one of the stations for conditioning certain of said signalling equipment at that station for operation, means for then transmitting over the line from said station impulses characterizing any other station on said line, means at the exchange for receiving said impulses and transmitting over the line a single station selecting impulse of variable polarity and duration, the polarity and duration of said station selecting impulse depending upon the impulses received from said one station, and means operated by said selecting impulse for conditioning certain of said signalling equipment at the characterized station for operation.

16. In a telephone or like system, an exchange, a party line terminating at the exchange, a plurality of stations on said line each having normally disabled signalling equipment, means at each of said stations for initiating calls, means at the exchange responsive to the operation of said means at one of the stations for conditioning certain of said signalling equipment at that station for operation, means for then transmitting over the line from said one station impulses characterizing any other station on said line, means at the exchange for receiving said impulses and transmitting over the line a single station selecting impulse of variable polarity and duration, the polarity and duration of said station selecting impulse depending upon the impulses received from said one station, means controlled by said selecting impulse for conditioning certain of said signalling equipment at the characterized station for operation, and other means controlled by said selecting impulse for maintaining the signalling equipment at said one station conditioned for operation.

17. In a telephone or like system, an exchange, a party line terminating at the exchange, a plurality of stations on said line each having a device normally disconnected from the line, means

at each of said stations for connecting the device at that station to the line only upon receipt over the line of a single station selecting impulse of a particular duration, means at any calling one

- 5 of said stations for transmitting over the line to the exchange impulses characterizing that station and other impulses characterizing the wanted station, means at the exchange controlled by the impulses characterizing the calling station
- 10 for transmitting over the line a station selecting impulse of the proper duration to cause the device at said calling station to be connected to the line, and other means at the exchange controlled by the impulses characterizing the wanted station
- 15 if same is another station on said party line for transmitting over the line a station selecting impulse of the proper duration to cause the device at said wanted station to be connected to the line.
- 20 18. In a telephone or like system, an exchange, a party line terminating at the exchange, a plurality of stations on said line each having a device normally disconnected from the line, means at each of said stations for connecting the device at that station to the line only upon receipt over the line of a single station selecting impulse of a particular polarity and duration, means at any calling one of said stations for transmitting over the line to the exchange impulses characterizing that station and other impulses characterizing the wanted station, means at the exchange controlled by the impulses characterizing the calling station for transmitting over the line a station selecting impulse of the proper polarity
- 25 and duration to cause the device at said calling station to be connected to the line, and other means at the exchange controlled by the impulses characterizing the wanted station if same is another station on said party line for transmitting over the line a station selecting impulse of the proper polarity and duration to cause the device at said wanted station to be connected to the line.
- 30 19. In a telephone or like system, an exchange, a party line terminating at the exchange, a plurality of stations on said line each having conversational equipment, means at each station normally disabling the conversational equipment
- 35 thereof, means at each station for rendering the disabling means thereof ineffective only upon receipt over the line of a single selecting impulse of a particular duration, means at any calling one of said stations for transmitting over the line to the exchange impulses characterizing that station and other impulses characterizing the wanted station, means at the exchange controlled by the impulses characterizing the calling station for transmitting over the line a selecting impulse of the proper duration to render the disabling means at said calling station ineffective, and other means at the exchange controlled by the impulses characterizing the wanted station if same is another station on said party line for transmitting over the line a selecting impulse of the proper duration to render the disabling means at the wanted station ineffective.
- 40 20. In a telephone or like system, an exchange, a party line terminating at the exchange, a plurality of stations on said line each having conversational equipment, means at each station normally disabling the conversational equipment
- 45 thereof, means at each station for rendering the disabling means thereof ineffective only upon receipt over the line of a single selecting impulse
- 50
- 55
- 60
- 65
- 70
- 75

of a particular polarity and duration, means at any calling one of said stations for transmitting over the line to the exchange impulses characterizing that station and other impulses characterizing the wanted station, means at the exchange controlled by the impulses characterizing the calling station for transmitting over the line selecting impulse of the proper polarity and duration to render the disabling means at said call-

ing station ineffective, and other means at the exchange controlled by impulses characterizing the wanted station if same is another station on said party line for transmitting over the line a selecting impulse of the proper polarity and duration to render the disabling means at the wanted station ineffective.
